HEATER FOR HAIR DRYING APPARATUS

Leon F. Willat, Mill Valley, Calif.
(1077 Howard St., San Francisco, Calif.)

Filed Mar. 9, 1961, Ser. No. 64,207

Term of patent 14 years
(Cl. D86—10)

FIG. 1 is a perspective view of a heater for hair drying apparatus showing my new design;

FIG. 2 is a front elevational view thereof; and

FIG. 3 is a top plan view.

I claim:

The ornamental design for a heater for hair drying apparatus, as shown.
